CLAIM

The ornamental design for an article of headwear that includes a concussion sensor and a noise reduction element, as shown and described.

DESCRIPTION

FIG. 1 is a top right side perspective view of the invention; FIG. 2 is a bottom right side perspective view thereof;

FIG. 3 is a bottom left side perspective view thereof;

FIG. 4 is a front view thereof;

FIG. 5 is a rear view thereof;

FIG. 6 is a left side view thereof;

FIG. 7 is a top view thereof;

FIG. 8 is a bottom view thereof; and,

FIG. 9 is a top right side perspective view thereof with unclaimed game play instruction projected on the visor.

The broken lines shown in the drawings show unclaimed subject matter only and form no part of the claimed design.
